L. F. SCHERZINGER.
LOOSE LEAF BINDER.
APPLICATION FILED JULY 8, 1909.

974,831.

Patented Nov. 8, 1910.

UNITED STATES PATENT OFFICE.

LAWRENCE F. SCHERZINGER, OF CHICAGO, ILLINOIS, ASSIGNOR TO THE TENGWALL COMPANY, OF CHICAGO, ILLINOIS, A CORPORATION OF MAINE.

LOOSE-LEAF BINDER.

974,831.

Specification of Letters Patent.

Patented Nov. 8, 1910.

Application filed July 8, 1909. Serial No. 506,466.

To all whom it may concern:

Be it known that I, LAWRENCE F. SCHERZINGER, a citizen of the United States, residing at 119 Cullom avenue, Chicago, county 5 of Cook, and State of Illinois, have invented certain new and useful Improvements in Loose-Leaf Binders, of which the following is a specification.

This invention relates to improvements 10 in loose leaf binders and refers more particularly to improved locking mechanism for binders or files of the prong type.

Among the salient objects of the invention are to provide a construction in which 15 the hinge leafs carrying the prong members are forced open by simple cam mechanism, and are positively locked in either open or closed position; to provide a construction in which the operating mechanism is substantially concealed within the binder, and in which the hinge leafs remain in open or closed position without manual control, thereby permitting the use of both hands 20 for inserting the leaves upon the binder; to provide a construction the locking mechanism of which may be used on different styles of binders; to provide an extremely simple and reliable construction which can be manufactured at a very low cost; and in 25 general to provide an improved construction of the character referred to.

The invention consists in the matters hereafter described and more particularly pointed out in the appended claims.

35 In the drawings—Figure 1 is a perspective view of a temporary binder of the prong type equipped with my invention, the covers being open and the sheet-holding prongs closed. Fig. 2 is the top plan view of the 40 binder proper, the cover plate being, however, removed, in order to bring out certain details of construction. Fig. 3 is a longitudinal vertical sectional view of the binder. Fig. 4 is a transverse sectional view showing 45 the prongs closed and Fig. 5 is a view showing the prongs open.

Referring to the drawings, 1, 1 designates the covers of the binder having an integral back 3. Lying inside of the back is a connecting strip 4, the ends of which are suitably secured to the covers as shown at 5. This strip 4 is fastened between the curved supporting plate 6 and a clamping plate 7 by means of rivets 8. The longitudinal

edges of the curved plate 6 are provided 55 with spaced apart hinge strips or knuckles 9, 9 clamped around the pintles 10, 10. To these pintles are pivotally connected the hinge plates 11 by means of knuckles 12 which register with the alternately disposed 60 knuckles 9 upon the supporting plate. The hinge plates or strips are provided with the usual prongs 13, 13 to which the leaves are fastened in the usual manner. The hinge plates 11 are normally forced into alignment, thus closing the prongs, by means of coiled springs 14 mounted upon the pintles and provided with fingers 15 which engage the upper face of the corresponding hinge plates. 70

Describing now the locking mechanism for holding the prongs in either open or closed position, within the upper face of the curved supporting plate 6 is mounted a sliding bar or arm 16; the ends of which are 75 provided with closed slots 17 riding in suitable confining studs or guide screws 18. The outer end of the arm is provided with an up-standing handle 19 whereby the arm may be reciprocated across the face of the curved 80 supporting plate 6.

As an important feature of construction the arm 16 is provided with wedge shaped cams 20 normally projecting through suitable apertures 21 formed by cutting away 85 the meeting edges of the hinge plates 11. In order to positively lock or clamp the hinge plates in closed position the cams are each provided with a locking lip or tongue 22 which project over the meeting edges of the 90 hinge plates when the latter are in closed position as shown at 23. The hinge plates are limited in their upward movement by means of a downwardly curved closure plate 24, the edges of which are crimped over the 95 hinge knuckles as shown at 25. This upper member 24 is slotted as shown at 26 at points opposite the prongs 13 in order that the latter may project through the plates as shown in Fig. 1. The arrangement is such that the 100 cover plate 24 co-operates with the back of the binder to substantially conceal all of the working parts.

The operation of the device is apparent from the above description. When it is desired to open the prongs to insert the leaves, the arm 16 is drawn back until the cams pass out of the slots 21 whereupon the hinge

plates will be obviously lifted and the prongs swung apart. They will remain in this position until the arm 16 is again forced back to its original position whereupon the cam 5 will reenter the slots and the hinge plates return to normal through the action of the springs. At the same time the locking lips will ride up over the meeting edges of the plates and positively lock the latter in closed position.

10 The invention is not limited to the details of construction shown except as set forth in the appended claims.

I claim as my invention:

15 1. In a binder, the combination with a supporting plate, of pronged carrying members hinged thereto and provided with a plurality of opposed prongs, an actuating arm slidably mounted in said supporting plate, 20 and cam blocks carried by said arm and projecting through slots formed in the meeting edges of said prong carrying members when the latter are in closed position.

25 2. In a binder, the combination with a supporting frame member, of prong plates hinged thereto and provided with a plurality of opposed prongs, an actuating arm slidably mounted in said frame member, and cam blocks carried by said arm and moving

beneath said plates to force the latter upwardly into open position.

3. In a binder, the combination with a pair of prong plates, of prongs carried thereby, a sliding cam for supporting said plates to open the prongs, and a locking lip carried by said cam for positively locking said prongs in closed position.

4. In a binder, the combination with a supporting frame member, of leaf carrying plates hinged thereto, an actuating arm slidably mounted beneath said plates and a cam block carried by said arm and projecting through an aperture formed in the meeting edges of said plates when the latter are in closed position.

45 5. In a binder, the combination with a supporting plate, of prong carrying members hinged thereto and provided with opposed prongs, an actuating arm slidably mounted beneath said plates, a cam block 50 carried thereby, a confining plate, and a flexible cover attaching member secured between said confining and supporting plates.

LAWRENCE F. SCHERZINGER.
